[57] **CLAIM**

The ornamental design for a baby bottle holder, as shown and described.

DESCRIPTION

FIG. 1 is a perspective view of the baby bottle holder showing my new design, with the bottle shown in broken lines for illustrative purposes only and forming no part of the claimed design;

FIG. 2 is a front elevational view of the baby bottle holder.

FIG. 3 is a rear elevational view thereof.

FIG. 4 is a left side elevational view thereof.

FIG. 5 is a right side elevational view thereof.

FIG. 6 is a top plan view of the baby bottle holder; and

FIG. 7 is a bottom plan view thereof.
